LUMINAIRE LENS

Herbert A. Fouke, Newark, Ohio, assignor to Holophane Company, Inc., New York, N.Y., a corporation of Delaware

Original design application May 25, 1964, Ser. No. 80,119, now Patent No. 204,484, dated Apr. 19, 1966. Divided and this application Mar. 3, 1966, Ser. No. 2,709

Term of patent 14 years

(Cl. D48—16)

This application is a division of copending application Ser. No. 80,119 filed May 25, 1964 and now Patent Ser. No. D-204,484.

FIG. 1 is a plan view of the light incident surface of a luminaire lens incorporating the light diffusing flute pattern of the invention;

FIG. 2 is a plan view of the light emergent surface of the lens of FIG. 1;

FIG. 3 is an enlarged view of the upper left quarter of FIG. 1 and showing the orientation of the flutes in greater detail, the design appearance of the remaining three-quarters of the lens appearing as shown;

FIG. 4 is an enlarged view of the upper right hand quarter of FIG. 2 and showing the light emergent prisms in detail, the design appearance of the remaining three-quarters of the lens appearing the same as shown;

FIG. 5 is an enlarged sectional view taken along the line 5—5 of FIG. 1;

FIG. 6 is a view similar to the view of FIG. 3 showing a quarter portion of a modification of the invention as applied to a lens having smaller dimensions than the lens of FIGS. 1-5 and showing the orientation of the diffusing flute pattern on the light incident surface thereof; and

FIG. 7 is a section taken along the line 7—7 of FIG. 3.

I claim:

The ornamental design for a luminaire lens, substantially as shown and described.
